Tea Service.

UNITED STATES PATENT OFFICE.

ELIZABETH A. BIXLER, OF SAN FRANCISCO, CALIFORNIA.

DESIGN FOR A TEA-URN.

SPECIFICATION forming part of Design No. 11,964, dated September 14, 1880.

Application filed May 11, 1880. Term of patent 7 years.

To all whom it may concern:

Be it known that I, ELIZABETH A. BIXLER, residing at San Francisco city and county, State of California, have invented and produced a new and original Design for a Tea-Urn, of which the following is a specification, reference being had to the accompanying photograph, in which the figure is a view of my newly-designed urn.

10 My design is intended for a containing vessel or urn for tea which is adapted to be used at social gatherings, known as "kettle-drums;" hence the form and nature of my design.

15 The leading feature of my design is the bowl or containing-vessel A, which is in the form of a kettle-drum, the flat top or lid of which, B, represents the parchment drum-head. Around the sides or rim are the tension-screws C, by which the head of the drum is drawn 20 tight. Crossed drumsticks D stand upon the center of the drum-head to serve as an ornamental handle to the lid. The cock or faucet through which the contents are drawn from the vessel has the thumb-piece E, by which it 25 is turned to open or close it, formed to represent a sheet or scroll of music. The vessel or drum is supported upon a tripod formed of three muskets or rifles, F, which have their butts resting upon a base-plate, G, while their

muzzles are separated, so as to support the 30 drum between them. The lamp H, by which the vessel is heated, is introduced between the butts of the rifles, and the wick-tube I curves up around them, as shown, and the whole is formed to represent a camp-fire, if desired. 35

Having thus described my invention, what I claim as my design is—

1. The design for a tea-urn, consisting of the kettle-drum A, with the screws C and drumsticks D, and the cock or faucet E, substantially as herein shown and described. 40

2. The design for a tea-urn, consisting of the kettle-drum A, with its supporting crossed rifles F and base-plate G, substantially as shown and described. 45

3. The design for a tea-urn, consisting of the kettle-drum A, with its cock or faucet E, the supporting crossed rifles F, base-plate G, and the lamp H, substantially as herein shown and described. 50

In witness whereof I have hereunto set my hand.

ELIZABETH A. BIXLER.
